UNITED STATES PATENT OFFICE.

HAROLD ALTON DAVIS AND PAUL SILIS NEWCOMER, OF FOSTORIA, OHIO.

ELEVATOR HOIST.

Application filed April 8, 1922. Serial No. 550,830.

To all whom it may concern:

Be it known that we, HAROLD ALTON DAVIS and PAUL SILIS NEWCOMER, citizens of the United States, residing at Fostoria, in the county of Seneca and State of Ohio, have invented certain new and useful Improvements in Elevator Hoists, of which the following is a specification.

This invention relates to elevator hoists and is especially adapted for use in connection with rope elevators for the purpose of raising and lowering hand elevators, electrically.

With the foregoing and other objects in view that will appear as the nature of our invention is better understood, the same consists in the novel features of construction, combination and arrangement of parts illustrated in the accompanying drawings and 20 more particularly pointed out in the appended claim.

In the accompanying drawings, which are for illustrative purposes only, and are therefore not drawn to scale:—

25 Figure 1 is a diagrammatic view, illustrating the application of our invention.

Figure 2 is an elevational view of our hoist.

Figure 3 is a vertical transverse section, 30 taken on line 3—3 of Figure 2, looking in the direction indicated by the arrow.

Figure 4 is an inside face view of one of the castings.

Referring to the drawings for a more particular description of our invention and in which drawings like parts are designated by like reference characters throughout the several views, A represents the elevator shaft, B the elevator and C our improved hoist or attachment, as a whole. This attachment 40 comprises a horizontal frame 1 consisting of a pair of corresponding laterally spaced angle bars 2, one end, as 3, of which frame is bolted to the elevator frame and the opposite end of which is bolted, as at 4, to the vertical depending portions 5 of a pair of corresponding laterally spaced castings 6 formed with the forked upper end portions 7, the tines or arms 8 of which are recessed, as at 9, to receive the bearings for the shaft 10. This shaft is disposed in a horizontal plane above and in parallel relation with the supporting frame 1 and is provided at one end with a worm 11 mounted thereon between the inner edges of the arms 8 of the

forked upper end portions of said castings and intermeshing with the teeth of the main gear wheel 12, carried by the driving shaft 13. The lower ends of the castings 5 are recessed, as at 14, to receive the upper halves 60 or sections 15 of the bearings for the shaft 13, the lower sections 16 of said bearings being mounted or seated in removable bearing-heads or plates 17 bolted or otherwise secured to the lower ends of the castings 5. 65 A motor 18 is mounted on the supporting frame 1 and its shaft 19 connected with the worm shaft 10 by the coupling 20. This motor is controlled by the switch 21 and it will be apparent that by moving the handle 22 either to the left or right, the elevator platform will be caused to rise or descend. When the handle 22 of the switch is released it automatically returns to neutral position. The castings are provided on their outer faces 75 with the reinforcing ribs 24, and it will be apparent that the arrangement of the several parts of our attachment is such that the motor and drive shaft are held in perfect alignment while the bearings for the shaft 80 13 are also held in alignment with each other; also, that the worm 11 being positioned between the arms of the forked upper end portions of the castings will hold the drive shaft 10 against any longitudinal play 85 or movement.

From the foregoing description taken in connection with the drawings, it is thought that the construction, operation and advantages of our invention will be thoroughly understood without requiring a more extended explanation.

Having described our invention, what we claim as new and desire to secure by Letters Patent, is:—

In combination with a beam, substantially Y-shaped brackets mounted thereon and at the opposite sides thereof, a shaft journaled between the upper branches of the brackets and carrying a worm which is located between the branches, a shaft journaled in the lower portions of the brackets and a worm wheel mounted upon the last mentioned shaft and having a peripheral portion meshing with the worm.

In testimony whereof we affix our signatures.

HAROLD ALTON DAVIS.
PAUL SILIS NEWCOMER.
